AUTOMATIC CONTROL DEVICE

Application filed April 4, 1930. Serial No. 441,702.

This invention relates to the automatic control of pressure and may be applied in numerous ways to automatically maintain the pressure of a fluid at some predetermined point. In the particular form of the invention herein described, I maintain a predetermined pressure in a steam boiler by automatically changing the position of a damper, which damper controls the heat input to the boiler. The pressure in the boiler is transmitted to a Bourdon spring, any change in the position of which spring will open or close the proper electric circuit to actuate the damper as required to maintain the desired pressure in the boiler. The opening and closing of these circuits is accomplished in a novel manner by the use of a special form of relay in combination with a galvanometer and thermo-couples, all in a manner which will be described.

Figure 1 illustrates the entire apparatus diagrammatically, the relays and galvanometer being shown in plan and the remaining components in elevation.

Figures 2 and 3 illustrate two positions of a special form of mercury switch, three of which form part of each of the relays. The mercury switches will hereinafter be referred to as connectors.

In Figure 1, I have illustrated a portion of a boiler 1 containing water 2. The boiler may be of any type, the water in which is evaporated by the heat from a furnace not shown. The products of combustion from the furnace leave the boiler through a flue 8, the rate of combustion in the furnace being controlled by a damper 7. The damper is so located in the flue that the rate of flow of gas through the flue may be increased or decreased respectively by lowering or lifting the damper arm 9, the damper being fully closed when the arm 9 has been lifted forty-five degrees from the horizontal. The lifting and lowering of the arm 9 is caused by a reversible motor 3 which communicates with a pulley 5 through a properly designed reducing gear in a gear case 4. To the pulley 5 is fastened a wire or similar flexible connection 6 which passes over guide pulleys 11 and 12, and is fastened to the arm 9 as illustrated, the wire

6 being kept taut by a counter-weight 10. It is thus obvious that as the motor 4 operates in one direction the damper 7 will slowly open, and as the motor operates in the opposite direction the damper will slowly close. 55

The electric circuits which operate the motor 3 in one direction or the other are controlled by two relays A and B. These relays, which will be presently described in detail, are similar in construction, and consist respectively of three tiltably mounted connectors 17, 19, and 20 which may be tilted by the action of an electro-magnet 21, and three tiltably mounted connectors 22, 24, and 25 which may be tilted by the action of an 65 electro-magnet 26.

Figures 2 and 3 illustrate connectors 17, 19, 20, 22, 24, and 25 in detail and in different positions. Each connector is of the same construction and consists of mercury 27, Figure 2, hermetically sealed in a glass tube 28. Near one end of the tube is a pocket 29. Into the end of the tube nearest the pocket is sealed a wire 30 which extends into the pocket as illustrated and protrudes outside of the tube 70 at 31 as a means for making electrical connection with the mercury inside of the tube. Likewise there is another wire 32 sealed into the tube at the other end, and which also extends into the mercury and protrudes outside 75 of the tube at 33 for making electrical connection with the mercury. It is obvious that if the connector is tilted as illustrated in Figure 2, an electric current will be permitted to flow through the mercury between 31 and 32, 80 while if the connector is tilted in the opposite direction, as illustrated in Figure 3, the mercury will break into two globules, some of it remaining in the pocket 29 thus breaking electrical connection between 31 and 33. 85

The connectors 17, 19 and 20 of relay A, Figure 1, are fastened to a tilttable frame 34 which frame is pivoted in bearings 35 and 36. These bearings are fastened to a base plate 37. An armature 38 with which the electro- 95 magnet 21 may react is permanently fastened to the tilttable frame 34. The tilttable frame is held in its normal position by a spring 39 which pulls the armature 38 away from the magnet 21 until it touches an adjustable 100

screw 40. The tension of the spring 39 is also adjustable by means of a screw 41. Both screws 40 and 41 are supported by a bracket 52 which bracket is fastened to the base plate 37. The magnet 21 is also fastened to the base plate 37 by means of a bracket 42. It thus follows that when the magnet 21 is energized, the tiltable frame 34, including the connectors 17, 19, and 20 will be tilted in one direction by reaction with the armature 38, and when the magnet 21 is deenergized, the frame 34 and its connectors will be tilted back to normal position by the spring 39, in which position as previously stated, the armature 38 rests against the adjusting screw 40.

In like manner the connectors 22, 24, and 25 of relay B are fastened to a tiltable frame 43 which frame is pivoted in bearings 44 and 45. These bearings are fastened to a base plate 46. An armature 47 with which the electro-magnet 26 may react is permanently fastened to the tiltable frame 43. The tiltable frame 43 is held in its normal position by a spring 48 which pulls the armature 47 away from the magnet 26 until it touches an adjustable screw 51. The tension of the spring 48 is also adjustable by means of a screw 50. Both screws 50 and 51 are supported by a bracket 134 which bracket is fastened to the base plate 46. The magnet 26 is also fastened to the base plate 46 by means of a bracket 53. It thus follows that when the magnet 26 is energized, the tiltable frame 43, including its connectors 22, 24 and 25 will be tilted in one direction by reaction with the armature 47, and when the magnet 26 is deenergized, the frame 43 and its connectors will be tilted back to normal position by the spring 48, in which position, as previously stated, the armature 47 rests against the adjustable screw 51.

Connectors 17, 19 and 20 of relay A are fastened to the tiltable frame 34 by means of a clamp 54. The connectors 19 and 20 are fastened in such a position that electrical connection is made through the mercury, as illustrated in Figure 2, when they are tilted by the magnet 21, and that electrical connection is broken through the mercury, as illustrated in Figure 3, when they are tilted back to normal position by the spring 39. On the other hand, connector 17 is fastened to the tiltable frame so that when tilted by the magnet 21, electrical connection through the mercury will be broken as illustrated in Figure 3, and when tilted back to normal position by the spring 39, electrical connection is made through the mercury as illustrated in Figure 2.

Similarly connectors 22, 24 and 25 of relay B are fastened to the tiltable frame 43 by means of a clamp 55. The connectors 24 and 25 are fastened in such a position that electrical connection is made through the mercury, as illustrated in Figure 2, when they are tilted by the magnet 26, and that

electrical connection is broken through the mercury, as illustrated in Figure 3, when they are tilted back to normal position by the spring 48. On the other hand, connector 22 is fastened to the tiltable frame 43 so that when tilted by the magnet 26, electrical connection through the mercury will be broken as illustrated in Figure 3, and when tilted back to normal position by the spring 48, electrical connection is made through the mercury as illustrated in Figure 2. In order to facilitate the tracing of the different circuits which include the connectors I have labeled each connector with an arrow. Those connectors whose arrows point in the direction of tilting as caused by the magnet, close a circuit when tilted by the magnet and open the circuit when tilted by the spring, while those connectors whose arrows point in the direction of tilting as caused by the spring, open a circuit when tilted by the magnet and close the circuit when tilted by the spring.

It thus follows that when magnet 21 is energized, the circuit through connectors 19 and 20 will be closed, and that when magnet 26 is energized, the circuit through connectors 24 and 25 will be closed. These connectors 19 and 20, and 24 and 25 constitute a reversing switch for the motor 3. This motor is series wound and is operated from any source of current as from a battery 113. The wires 114 and 115 are connected with the brushes of the motor while the wires 116 and 117 are connected with the field. The wires which connect the motor with connectors 19 and 20 of relay A, and connectors 24 and 25 of relay B are shown in heavy lines to contrast them from the rest of the circuits. They are connected in the well known manner so that when the circuit is closed through the connectors 19 and 20 by the action of magnet 21, the motor will run in one direction, and when the circuit is closed through the connectors 24 and 25 by the action of magnet 26, the motor will run in the opposite direction.

Either of the electric circuits which actuates the magnet 21 or magnet 26 may be closed by the indicating needle 56 of a galvanometer 57. The galvanometer 57 is of the well known form which consists of a permanent magnet 74 between the poles of which is pivoted a coil 75. The indicating needle 56 is attached to the pivoted coil 75 in the usual manner while the turning moment of the coil as caused by the current passing through it, is counter-balanced by a hair spring 76. The circuit which includes the magnet 21 of relay A is closed by electrical contact between the needle 56 and a contact disc 61. The contact disc 61 is carried by an adjustable rod 58 which is mounted on an insulated support 59. The circuit which includes the magnet 26 of relay B is closed by electrical contact between the needle 56 and a contact disc 64, the contact disc 64 being carried by an ad-

justable rod 62 which is mounted on an insulated support 63. The circuit which energizes the magnet 21 of relay A starts at battery 65, thence through wire 79 to a limiting switch which will be referred to later and which consists of a blade spring 84 to which is fastened a contact piece 129, and a second contact piece 130 fastened to a stationary arm 83. From the limiting switch the circuit continues through wires 23 and 18 to a binding post 71, from the binding post 71 through an electrical resistance 72 (to be referred to later) to a binding post 73, from binding post 73 through the hair spring 76 of the galvanometer to the needle 56. When the needle 56 touches the contact disc 61, the circuit continues through the rod 58, and wire 66 to a binding post 67, from the binding post 67 through a flexible connection 68, the connector 17 and a flexible connection 69 to the magnet 21, and from magnet 21 through wire 70 back to the battery 65. Similarly the circuit which energizes the magnet 26 of relay B starts at battery 60, thence through wire 88 to a limiting switch which will be referred to later and which consists of a blade spring 85 to which is fastened a contact piece 128, and a second contact piece 127 fastened to a stationary arm 82. From the limiting switch the circuit continues through wire 18 to the binding post 71, from the binding post 71 through the electrical resistance 72 to the binding post 73, from binding post 73 through the hair spring 76 of the galvanometer to the needle 56. When the needle touches the contact disc 64 the circuit continues through rod 62 and wire 77 to a binding post 78, from the binding post 78 through a flexible connection 49, the connector 22 and a flexible connection 80 to the magnet 26, and from magnet 26 through wire 81 back to the battery 60. The manner in which the relays A and B function depending upon whether the needle 56 of the galvanometer touches the disc 61 or 64, and the manner in which electrical contact between the needle 56 and one or the other of the discs 61 and 64 is assured, will be presently described in complete detail.

The current which deflects the needle 56 of the galvanometer is created in two thermo-couples 90 and 91 which are connected in opposition as illustrated. The circuit which includes the thermo-couples and the galvanometer continues from the lead 95 of couple 91, through wire 93 to the binding post 71, from binding post 71 through the resistance 72 to binding post 73, from the binding post 73 to the hair spring 76, from the hair spring 76 through the pivoted coil 75 to binding post 89, from binding post 89 through wire 97 to the lead 92 and thence back to the couples. The thermo-couples 90 and 91 are kept at a constant temperature, or nearly so, by an electric heating coil 15 which receives its

power from any source as from a battery 13 through wires 14 and 16. The couples are electrically opposed to each other as will be noted from the plus symbol on each of the leads 92 and 95, and the minus symbol on each of the leads 93 and 94. In other words the couples 90 and 91 are so included in the circuit with the galvanometer that the electro-motive force of one of the couples neutralizes the electro-motive force of the other. The deflection of the galvanometer in one direction or the other as caused by the thermo-couple, depends upon the short circuiting of one or the other of the couples, all in a manner to be presently described.

The difficulty of making electrical contact between two contact surfaces by means of a delicate pressure such as exerted by the delicate needle 56 of the galvanometer against one or the other of the discs 61 and 64 has long been realized. It is to eliminate this difficulty that I have provided the electrical resistance 72 already referred to. The trouble that is experienced when a delicate needle is used to close an electric circuit, as for example when the needle 56 is deflected against the disc 61, is that the delicate pressure exerted by the needle against the disc is not sufficient to permit the required amount of current to flow. The circuit which is closed by contact between the needle 56 and the disc 61 includes the connector 17 and magnet 21 of relay A, also battery 65 and the resistance 72. This circuit has already been traced. Although the delicate pressure between the needle 56 and the disc 61 may not cause sufficient current to flow to actuate the magnet 21, it will nevertheless cause some current to flow through the circuit which includes the connector 17, magnet 21, battery 65, resistance 72, hair spring 76, needle 56, and disc 61. Regardless of how small this flow may be, it will obviously cause a drop or difference in potential across the resistance 72. This drop or difference in potential will cause a slight flow of current from the resistance through binding post 73, the hair spring 76 and the pivoted coil 75 to binding post 89, from binding post 89 through wire 97 and lead 92 to couple 90, from couple 90 through the leads 93 and 94 to couple 91, and from couple 91 through the lead 95, wire 96 and binding post 71 back to the resistance. The polarity of battery 65 is such that the flow of current just described is in the proper direction through the galvanometer to force the needle 56 tighter against the disc 61. The increased pressure between the needle 56 and the disc 61 will increase the flow through the magnet 21 and through the resistance 72. The increased flow through the resistance 72 will again increase the drop across the resistance which, in the manner just described, will again increase the pressure between the needle 56 and the disc 61, and this increased pres-

sure will obviously still further increase the flow of current through the circuit which includes the magnet 21 and the resistance 72. In other words as soon as there is the slightest contact between the needle 56 and the disc 61, the pressure between the needle and the disc will instantly build up, in the manner just described, until sufficient current flows through the magnet 21 to tilt the connectors 17, 19 and 20 of relay A. As soon as connector 17 has been tilted, the circuit through it and the magnet 21 will be broken thereby deenergizing the magnet 21 and permitting the spring 39 to tilt the connectors back to normal position. If the needle 56 still touches the disc 61, the same action will repeat itself. In other words so long as the needle 56 touches the disc 61, so long will the relay A continue to oscillate in the manner just described. The oscillation of the relay A will alternately close and open the circuit through the connectors 19 and 20 which circuit as previously described operates the motor 3 in the proper direction to close the damper 7.

In like manner, the circuit which is closed by contact between the needle 56 and the disc 64 includes the connector 22 and magnet 26 of relay B, also battery 60 and resistance 72. This circuit has already been traced. Although the delicate pressure between the needle 56 and the disc 64 may not cause sufficient current to flow to actuate the magnet 26, it will nevertheless cause some current to flow through the circuit which includes the connector 22, magnet 26, battery 60, resistance 72, hair spring 76, needle 56 and disc 64. Regardless of how small this flow may be, it will obviously cause a drop or difference in potential across the resistance 72. This drop or difference in potential will cause a slight flow of current from the resistance through binding post 71, wire 96 and lead 95 to couple 91, from couple 91 through leads 94 and 93 to couple 90, from couple 90 through lead 92 and wire 97 to binding post 89, and from binding post 89 through the pivoted coil 75, hair spring 76 and binding post 73 back to the resistance. The polarity of battery 60 is opposite to that of battery 65 and such that the flow of current just described is in the proper direction through the galvanometer to force the needle 56 tighter against the disc 64. The increased pressure between the needle 56 and the disc 64 will increase the flow through the circuit which includes the magnet 26 and the resistance 72. The increased flow through the resistance 72 will again increase the drop across the resistance which in the manner just described will again increase the pressure between the needle 56 and the disc 64, and this increased pressure will obviously still further increase the flow of current through the circuit which includes the magnet 26 and the resistance 72. In other words as soon as there is the slightest

contact between the needle 56 and the disc 64, the pressure between the needle and the disc will instantly build up, in the manner just described, until sufficient current flows through the magnet 26 to tilt the connectors 22, 24 and 25 of relay B. As soon as connector 22 has been tilted, the circuit through it and the magnet 26 will be broken, thereby deenergizing the magnet 26 and permitting the spring 48 to tilt the connectors back to normal position. If the needle 56 still touches the disc 64, the same action will repeat itself. In other words so long as the needle 56 touches the disc 64, so long will the relay B continue to oscillate in the manner just described. The oscillation of relay B will alternately close and open the circuit through the connectors 24 and 25 which circuit as previously described operates the motor 3 in the proper direction to open the damper 7.

The needle 56 of the galvanometer is so adjusted that its zero position is midway between the discs 61 and 64. In other words when there is no current flowing through the galvanometer, the position of the needle with respect to the contact discs will be as illustrated. It is obvious that if the couples 90 and 91 have the same characteristics, and if, as previously stated, they are electrically opposed as illustrated, then the electro-motive force of one neutralizes the electro-motive force of the other, irrespective of the temperature to which the couples may be heated by the heating coil 15 already referred to. On the other hand if the couple 91 is short-circuited as for example through wires 98 and 100, then the neutralizing effect of couple 91 will be eliminated and the electro-motive force of the couple 90 will be permitted to send a current to the galvanometer through the circuit already described. Likewise if the couple 90 is short-circuited as for example through wires 99 and 100, then the neutralizing effect of the couple 90 will be eliminated and the electro-motive force of the couple 91 will be permitted to send a current through the galvanometer. The polarity of the couple 90 is such that when the couple 91 is short-circuited, the current from couple 90 will deflect the needle 56 of the galvanometer against the disc 61 thereby closing the circuit which includes the connector 17 and the magnet 21, which circuit, in a manner already described, actuates the relay A to operate the motor 3 in the proper direction to close the damper 7. The polarity of the couple 91, on the other hand, is opposite to that of couple 90 and such that when the couple 90 is short-circuited, the current from the couple 91 will deflect the needle 56 of the galvanometer against the disc 64, thereby closing the circuit which includes the connector 22 and magnet 26, which circuit, in a manner already described, ac-

tuates the relay B to operate the motor 3 in the proper direction to open the damper 7.

Whether the couple 90, or the couple 91 is short-circuited depends upon whether the pressure in the boiler is below or above the predetermined pressure at which the steam in the boiler is to be maintained. This is accomplished by means of a Bourdon spring 107 which is connected with the pressure in the boiler through the tube 101. The tube 101 communicates with the Bourdon spring 107 through a hollow casting 108 which is held rigidly in place against the gear case 4 by means of a bracket 109. To the movable end of the Bourdon spring is fastened an extension arm 104 which extends to a point between two electrical contact screws 121 and 122 as illustrated. These screws are respectively carried by two extension arms 106 and 105. These arms are electrically insulated from each other and are supported in a manner which will be presently described. The arm 106 is electrically connected with the positive lead of the couple 91 through a flexible connection 98, while the arm 105 is electrically connected with the positive lead of the couple 90 through a flexible connection 99. The extension arm 104 which extends from the Bourdon spring 107 to a point between the two contact screws 121 and 122 is on the other hand electrically connected with the negative lead of each couple through the ground wire 100. The contact screws 121 and 122 are so adjusted that when the steam in the boiler is at the desired or predetermined pressure, the arm 104 will be very close to the extremity of each of the screws but touching neither of them. It thus follows that when the steam is at the predetermined pressure, neither of the couples will be short-circuited, there will be no flow through the galvanometer, and the needle 56 will be at zero or midway between the two contact discs 61 and 64. In this position of the needle 56, neither of the relays A and B will be actuated and the motor 3 will consequently be dead. On the other hand if the pressure in the boiler rises slightly above the predetermined pressure, the Bourdon spring 107 will obviously lift the arm 104 thereby establishing electrical contact between said arm and the screw 121. This contact short-circuits the couple 91 thus permitting the couple 90 to deflect the needle 56 against the disc 61. Contact between the needle 56 and the disc 61 actuates the relay A which operates the motor 3 in the proper direction to close the damper thereby decreasing the pressure in the boiler. Likewise if the pressure in the boiler drops slightly below the predetermined pressure, the Bourdon spring will obviously lower the arm 104, thereby establishing contact between said arm and the screw 122. This contact short-circuits the couple 90, thus permitting the couple 91 to deflect

the needle 56 against the disc 64. Contact between the needle 56 and the disc 64 actuates the relay B which operates the motor 3 in the proper direction to open the damper thereby increasing the pressure.

It is obvious from the above that when the pressure in the boiler is at a predetermined point the motor 3 which operates the damper will be dead but when the pressure in the boiler is below the predetermined point, the motor will operate to open the damper, and when the pressure in the boiler is above the predetermined point, the motor will operate to close the damper, all in the manner above described. It is however further obvious, that it takes some time for any boiler to respond to a definite change in damper adjustment. In other words a slight drop in the boiler pressure below normal might cause the damper to open full before the pressure responds to the increased heat input as caused by the wider damper opening. Likewise an increase in the pressure might cause the damper to close full or nearly so before the pressure responds to the decreased heat input as caused by the closing of the damper. Such action of the damper beyond the necessary point to produce the required result is what is known in practice as hunting action which is decidedly objectionable and detrimental to good control. To prevent such hunting, and to make it possible for the damper to open or close to the exact position required to maintain the pressure constant within very narrow limits under varying load conditions, I provide a wheel 118 which supports the insulated arms 105 and 106 already referred to. The wheel 118 is on the same shaft with a worm wheel 119, said shaft being carried in a bearing supported by a bracket 111, which bracket is fastened to the base 126 as illustrated. The worm wheel 119 meshes with a worm 120 which worm is fastened to the same shaft with the pulley 5. The wheel 118 will therefore turn in proportion to the motion of pulley 5, thereby lifting or lowering the contact screws 121 and 122 through an arc with the worm wheel 119 as a center. The wire 6 which connects the pulley 5 with the damper is so fastened to the pulley that as the motor 3 operates to open the damper, the contact screws 121 and 122 will be lowered, and when the motor operates to close the damper, said contact screws are lifted. It thus follows that if the pressure in the boiler increases, the Bourdon spring 107 will expand, thereby lifting the arm 104 which consequently makes contact with the screw 121. The electrical contact thus established short-circuits the couple 91 which in the manner already stated permits the couple 90 to deflect the galvanometer needle 56 against the disc 61 which closes the circuit to operate the motor in the proper direction to close the damper. As the pulley 5 turns to close the

damper; the wheel 118 turns in a clockwise direction, thereby lifting the arms 106 and 105 with their respective contact screws 121 and 122. The closing action of the damper 5 will continue only until contact between the arm 104 and the screw 121 is again broken at which time the galvanometer needle will again assume its normal position, as illustrated, thus causing the motor to stop. If 10 the closing of the damper by the action of the motor to this point is not sufficient to prevent a further increase in boiler pressure, then the increasing boiler pressure will again cause contact between the arm 104 and the 15 contact screw 121, and the motor will continue to operate to close the damper, at the same time still further lifting the screws 121 and 122 until contact between the arm 104 and the screw 121 is again broken, at which 20 time the motor will stop. If the new position of the damper now prevents a further increase in the boiler pressure, it is obvious that the position of the damper will remain unchanged. Likewise if the pressure in the 25 boiler decreases, the Bourdon spring will contract thereby lowering the arm 104 which consequently makes contact with the screw 122. The electrical contact thus established short-circuits the couple 90 which in the manner already stated permits the couple 91 to 30 deflect the galvanometer needle 56 against the disc 65 which closes the circuit to operate the motor in the proper direction to open the damper. As the pulley 5 turns to open 35 the damper, the wheel 118 turns in a counter-clockwise direction, thereby lowering the arms 106 and 105 with their respective contact screws 121 and 122. The opening action of the damper will continue only until contact between the arm 104 and the screw 122 is again broken at which time the galvanometer 40 needle will again assume its normal position, as illustrated, thus causing the motor to stop. If the opening of the damper by the 45 action of the motor to this point is not sufficient to prevent a further decrease in the boiler pressure, then the decreasing boiler pressure will again cause contact between the arm 104 and the contact screw 122, and the 50 motor will continue to operate to open the damper, at the same time still further lowering the screws 121 and 122 until contact between the arm 104 and the screw 122 is again broken, at which time the motor will 55 stop. If the new position of the damper now prevents a further decrease in the boiler pressure, it is obvious that the position of the damper will remain unchanged. It is evident from the above that by changing the position of the contact screws 121 and 122 in the manner described, the damper will open or close only to a point where the heat input as 60 controlled by the damper is balanced by the actual load on the boiler, thus eliminating 65 excessive damper motion as would otherwise

be caused by the lag in the boiler to respond to changes in the damper position.

In order to prevent the operation of the damper beyond the position in which it is fully closed, or beyond the position in which it is fully open, I provide two limiting switches which have already been referred to, one of which is included in the circuit with relay A and the other of which is included in the circuit with relay B. These switches are operated by a ball 86 fastened to the flexible wire 6. The wire 6 passes through a hole or slot in the blade spring 84 of the switch which limits the opening motion of the damper. This switch is fastened to a stationary rod 87 and is adjusted to the proper position with respect to the ball 86 so that as the ball rises due to the damper opening action of the motor, it will lift the blade spring 84 immediately after the damper is fully open. The lifting of the blade spring 84 breaks contact between the two contact pieces 129 and 130 thus opening the circuit which includes the relay A. The opening of this circuit will obviously stop the damper opening action of the motor even though the needle 56 of the galvanometer may still be touching the contact disc 61. Likewise the wire 6 passes through a hole or slot of the blade 85 of the switch which limits the closing motion of the damper. This switch is also fastened to the rod 87 and is adjusted to the proper position with respect to the ball 86 so that as the ball is lowered due to the damper closing action of the motor, it will push down the blade spring 85 immediately after the damper is fully closed. The pushing down of the blade spring 85 breaks contact between the contact pieces 127 and 128 thus opening the circuit which includes the relay B. The opening of this circuit will obviously stop the damper closing action of the motor even though the needle 56 of the galvanometer may still be touching the contact disc 64.

Although I have utilized a Bourdon spring as a matter of convenience in illustrating this invention, it is obvious that any movable element which is affected by changes in pressure may be used in place thereof for moving the arm 104 with respect to the contact screws. As substitutes for the Bourdon spring I might mention as examples, a piston, a diaphragm, a bellow, or a mercury column, any of which might be used instead of the Bourdon spring without in any way departing from the novelty of this invention. Furthermore although I have described only one application of this invention, there are obviously many others as for example, the automatic throttling of an inlet or outlet valve of a pressure chamber for the purpose of keeping a constant pressure within said chamber.

What I claim as new and desire to cover by Letters Patent is:

1. In a device of the class described, the combination with a chamber, of a movable element connected with the chamber and actuated by the pressure in the chamber, a contact piece with which the movable element makes electrical contact, two electrically opposed thermo-couples, a circuit which includes said couples, and a circuit which includes the movable element, the contact piece, and one of the thermo-couples. 5
2. In a device of the class described, the combination with a chamber, of a movable element which communicates with the chamber and is actuated by changes of pressure in the chamber, a contact piece with which the movable element makes electrical contact when it reaches a predetermined position, two electrically opposed thermo-couples, a circuit which includes said couples, a circuit 10 which includes the movable element, the contact piece and one of the thermo-couples, a second contact piece with which the movable element makes electrical contact when it reaches a second predetermined position, 15 and a circuit which includes the movable element, the second contact piece and the other thermo-couple. 20
3. In a device of the class described, the combination with a chamber, of a movable element actuated by changes of pressure in the chamber, a contact piece with which the movable element makes electrical contact when it reaches a predetermined position, two electrically opposed thermo-couples, a 25 circuit which includes the movable element, the contact piece and one of the thermo-couples, a galvanometer, and a second circuit which includes both thermo-couples and the galvanometer. 30
4. In a device of the class described, the combination with a chamber, of a movable element actuated by changes of pressure in the chamber, a contact piece with which the movable element makes electrical contact when 35 said element reaches a predetermined position, two electrically opposed thermo-couples, a circuit which includes the movable element, the contact piece, and one of the thermo-couples, a second contact piece for making electrical contact with the movable element when 40 said element reaches a second predetermined position, a second circuit which includes the movable element, the second contact piece, and the other thermo-couple, a galvanometer, and a third circuit which includes both thermo-couples and the galvanometer. 45
5. In a device of the class described, the combination with a chamber, of a movable element actuated by changes of pressure in the chamber, a contact piece with which the movable element makes electrical contact when 50 said element reaches a predetermined position, two electrically opposed thermo-couples, a circuit which includes the movable element, the contact piece, and one of the thermo-couples, a second contact piece, and one of the thermo-couples, a second contact piece for making electrical contact with the movable element when 55 said element reaches a second predetermined position, a second circuit which includes the movable element, the second contact piece, and the other thermo-couple, a galvanometer, and a third circuit which includes both thermo-couples and the galvanometer. 60
6. In a device of the class described, the combination with a chamber, of a movable element actuated by changes of pressure in the chamber, a contact piece with which the movable element makes electrical contact when 65 said element reaches a predetermined position, two electrically opposed thermo-couples, a circuit which includes the movable element, the second contact piece, and one of the thermo-couples, a second contact piece for making electrical contact with the movable element when 70 said element reaches a second predetermined position, a second circuit which includes the movable element, the second contact piece, and the other thermo-couple, a galvanometer, a third circuit which includes both thermo-couples, and the galvanometer, and means for heating the thermo-couples. 75
7. In a device of the class described, the combination with a chamber, of a Bourdon spring connected with the chamber, a contact piece with which the Bourdon spring makes electric contact when the pressure in the chamber reaches a predetermined point, two electrically opposed thermo-couples, a circuit which includes one of the thermo-couples, the contact piece and the Bourdon spring, a galvanometer, and a second circuit which includes the galvanometer and the thermo-couples. 80
8. In a device of the class described, the combination with a chamber, of a Bourdon spring connected with the chamber, a contact piece with which the Bourdon spring makes electric contact when the pressure in the chamber reaches a predetermined point, two electrically opposed thermo-couples, a circuit which includes one of the thermo-couples, the Bourdon spring, and the contact piece, a second contact piece with which the Bourdon spring makes electrical contact when the pressure in the chamber reaches a second predetermined point, a second circuit which includes the other thermo-couple, the second contact piece and the Bourdon spring, a galvanometer, and a third circuit which includes the galvanometer and both thermo-couples. 110
9. In a device of the class described, the combination with a thermo-couple, of a second thermo-couple in series with, but electrically opposed to the first thermo-couple, a galvanometer, a circuit which includes the galvanometer and the two thermo-couples, a chamber, a movable element actuated by the 125

pressure in the chamber, a contact piece with which the movable element makes electrical contact when it reaches a predetermined position, a circuit which includes the movable element, the contact piece and the first thermo-couple, a second contact piece for making contact with the movable element when said element reaches a second predetermined position, a circuit which includes the movable element, the second contact piece and the second thermo-couple, and means for changing the relative position of the contact pieces with respect to the movable element, independently of the pressure in the chamber.

10. In a device of the class described, the combination with a steam boiler, of a damper for controlling the heat input to the boiler, a movable element connected with and actuated by the pressure within the boiler, a contact piece with which the movable element makes contact when said element reaches a predetermined position, two electrically opposed thermo-couples, an electric circuit which includes one of the thermo-couples, the contact piece, and the movable element, a second contact piece with which the movable element makes electrical contact when said element reaches a second predetermined position, a second circuit which includes the other thermo-couple, the second contact piece and the movable element, a galvanometer having an indicating needle, a third electric circuit which includes the galvanometer and the two thermo-couples, a motor connected with the damper for operating same, a contact disc with which the needle of the galvanometer collides when deflected in one direction, a fourth circuit which includes the needle and the contact disc and which circuit controls the operation of the motor to close the damper, a second contact disc with which the needle of the galvanometer collides when deflected in the opposite direction, and a fifth circuit which includes the needle and the second contact disc and which circuit controls the operation of the motor to open the damper.

11. In a device of the class described, the combination with a steam boiler, of a damper for controlling the heat input to the boiler, a movable element connected with and actuated by the pressure within the boiler, a contact piece with which the movable element makes contact when said element reaches a predetermined position, two electrically opposed thermo-couples, an electric circuit which includes one of the thermo-couples, the contact piece, and the movable element, a second contact piece with which the movable element makes electrical contact when said element reaches a second predetermined position, a second circuit which includes the other thermo-couple, the second contact piece and the movable element, a galvanometer having an indicating needle, a third electric circuit which includes the galvanometer and the two

thermo-couples, a motor connected with the damper for operating same, a contact disc with which the needle of the galvanometer collides when deflected in one direction, a fourth circuit which includes the needle and the contact disc and which circuit controls the operation of the motor to close the damper, a second contact disc with which the needle of the galvanometer collides when deflected in the opposite direction, a fifth circuit which includes the needle and the second contact disc and which circuit controls the operation of the motor to open the damper, and a connection between the motor and the contact pieces for changing the position of said pieces in proportion to the number of revolutions of the motor and independently of the pressure in the boiler.

12. In a device of the class described, the combination with a steam boiler, of a damper for controlling the heat input to the boiler, a movable element connected with and actuated by the pressure within the boiler, a contact piece with which the movable element makes contact when said element reaches a predetermined position, two electrically opposed thermo-couples, an electric circuit which includes one of the thermo-couples, the contact piece, and the movable element, a second contact piece with which the movable element makes electrical contact when said element reaches a second predetermined position, a second circuit which includes the other thermo-couple, the second contact piece and the movable element, a galvanometer having an indicating needle, a third electric circuit which includes the galvanometer and the two thermo-couples, a motor connected with the damper for operating same, a contact disc with which the needle of the galvanometer collides when deflected in one direction, a fourth circuit which includes the needle and the contact disc and which circuit controls the operation of the motor, to close the damper, a second contact disc with which the needle of the galvanometer collides when deflected in the opposite direction, a fifth circuit which includes the needle and the second contact disc and which circuit controls the operation of the motor, to open the damper, a connection between the motor and the contact pieces for changing the position of said contact pieces in proportion to the number of revolutions of the motor and independently of the pressure in the chamber, a switch in the fourth circuit for opening and closing said circuit, an element for actuating said switch, operated by the motor, a second switch included in the fifth circuit, and an element for actuating the second switch, operated by the motor.

13. In a device of the class described, the combination with a chamber, of a movable element connected with the chamber and actuated by the pressure in the chamber, an elec-

trical contact piece with which the movable element makes electrical contact when it reaches a predetermined position, two electrically opposed thermo-couples, a circuit 5 which includes one of the thermo-couples, the contact, and the movable element, a second electrical contact with which the movable element makes electrical contact when it reaches a second predetermined position, a 10 second circuit which includes the other thermo-couple, the second contact and the movable element, a galvanometer having an indicating needle, an electrical resistance, a third circuit which includes the galvanometer 15 meter, the resistance, and the two thermo-couples, a contact piece with which the galvanometer needle makes electrical contact when deflected in one direction, a fourth circuit which includes the galvanometer needle, the 20 contact piece and the resistance, a second contact piece with which the galvanometer needle makes electrical contact when deflected in the opposite direction, and a fifth circuit which includes the galvanometer needle, the second 25 contact piece, and the resistance.

14. In a device of the class described, the combination with a chamber, of a movable element connected with the chamber and actuated by the pressure in the chamber, an 30 electrical contact with which the movable element makes electrical contact when it reaches a predetermined position, two electrically opposed thermo-couples, a circuit which includes one of the thermo-couples, the contact, 35 and the movable element, a second electrical contact with which the movable element makes electrical contact when it reaches a second predetermined position, a second circuit which includes the other thermo-couple, the second contact and the movable element, a galvanometer having an indicating 40 needle, an electrical resistance, a third circuit which includes the galvanometer, the resistance, and the two thermo-couples, a contact piece with 45 which the galvanometer needle makes electrical contact when deflected in one direction, a fourth circuit which includes the galvanometer needle, the contact piece and the resistance, a second contact piece with 50 which the galvanometer needle makes electrical contact when deflected in the opposite direction, a fifth circuit which includes the galvanometer needle, the second contact piece, and the resistance, a damper for throttling 55 the flow of gas through a flue, a motor connected with the damper for actuating same, the operation of said motor in one direction being controlled by the fourth circuit, and in the opposite direction by the fifth circuit.

15. In a device of the class described, the combination with a tiltable member, of an electro-magnet for tilting the member in one direction, a spring for tilting the member in the opposite direction, a switch actuated 60 by the tiltable member and which is opened by the tiltable member when said member is tilted by the magnet, and closed by the tiltable member when said member is tilted by the spring, a galvanometer having an indicating 65 needle, a contact piece with which the needle makes electrical contact when deflected in one direction, an electrical resistance, a circuit which includes the needle, the contact piece, the resistance, the magnet and the switch, a second tiltable member, a second electro-magnet for tilting the second tiltable member in one direction, a second spring for tilting the second tiltable member in the opposite direction, a second switch actuated by the second 70 tiltable member and which switch is opened by the member when said member is tilted by the second magnet, and closed by the member when said member is tilted by the spring, a second contact piece with which the needle of the galvanometer makes electrical contact when deflected in the opposite direction, a second circuit which includes the needle, the second contact piece, the resistance, the second magnet and the second switch, two electrical 75 opposed thermo-couples in series, a third circuit which includes the thermo-couples, the resistance and the galvanometer, a chamber, a movable element connected with the chamber and actuated by the pressure 80 therein, an electrical contact with which the movable element communicates when said element reaches a predetermined position, a fourth circuit which includes one of the thermo-couples, the contact and the movable element, a second electrical contact with which the movable element communicates when said element reaches a second predetermined position, and a fifth circuit which includes the other thermo-couple, the second contact and 85 the movable element.

16. In a device of the class described, the combination with a pressure chamber, of a Bourdon spring connected with and actuated by the pressure in the chamber, two electrical 90 contact screws, an arm fastened to the Bourdon spring and extending between the two screws, a motor, a connection between the motor and the screws for changing the position of the screws with respect to the arm, two electrically opposed thermo-couples, an electric circuit which includes one of the couples, one of the screws, and the arm, a second electric circuit which includes the other couple, the other screw and the arm, a galvanometer, and a third circuit which 95 includes both couples and the galvanometer, said third circuit controlling the operation of the motor.

17. In a device of the class described, the combination with a galvanometer having an indicating needle, of a contact piece with which the needle makes electrical contact when deflected in one direction, a second contact piece with which the needle makes elec- 100

- trical contact when deflected in the opposite direction, an electrical resistance, a motor, a relay with a primary and a secondary circuit, the primary circuit of which relay includes the needle, the first contact piece and the resistance, and the secondary circuit of which relay includes the motor to operate it in a given direction, a second relay having a primary and secondary circuit, the primary circuit of which relay includes the needle, the second contact piece and the resistance, and the secondary circuit of which relay includes the motor to operate it in the opposite direction, two electrically opposed thermo-couples, a circuit which includes the thermo-couples, the resistance and the galvanometer, a chamber, and means for short-circuiting one or the other of the thermo-couples, said means being actuated by the pressure in the chamber.
18. In a device of the class described, the combination with a galvanometer having an indicating needle, of a contact piece with which the needle makes electrical contact when deflected in one direction, a second contact piece with which the needle makes electrical contact when deflected in the opposite direction, an electrical resistance, a motor, a relay with a primary and a secondary circuit, the primary circuit of which relay includes the needle, the first contact piece and the resistance, and the secondary circuit of which relay includes the motor to operate it in a given direction, a second relay having a primary and secondary circuit, the primary circuit of which relay includes the needle, the second contact piece and the resistance, and the secondary circuit of which relay includes the motor to operate it in the opposite direction, two electrically opposed thermo-couples, a circuit which includes the thermo-couples, the resistance and the galvanometer, a chamber, means for short-circuiting one or the other of the thermo-couples, said means being actuated by the pressure in the chamber, a flue, a damper for throttling the flow of gas through the flue, and a connection between the motor and the damper for operating the latter.
19. In a device of the class described, the combination with a galvanometer, having two connecting terminals, of two thermo-couples, the negative leads of which are electrically connected, the positive lead of one of which is connected with one of the terminals of the galvanometer, the positive lead of the other of which is connected with the other terminal of the galvanometer, a chamber, a Bourdon spring connected with the chamber and actuated by the pressure therein, a contact piece with which the Bourdon spring makes electrical connection when it reaches a given position, a circuit which includes the Bourdon spring, the contact piece, and one of the couples, a second contact piece with

which the Bourdon spring makes electrical connection when it reaches a second given position, a circuit which includes the Bourdon spring, the second contact piece and the other couple, a throttling means for changing the pressure in the chamber, and a motor connected with the throttling means for operating same, said motor being controlled by the galvanometer.
